UNITED STATES PATENT OFFICE.

HERBERT O. RUSSELL, OF LOS ANGELES, CALIFORNIA, AND CHARLES L. PAULUS, OF DAYTON, OHIO.

LOCK MECHANISM FOR MACHINE GUNS.

Application filed June 9, 1922. Serial No. 567,074.

To all whom it may concern:

Be it known that we, HERBERT O. RUSSELL and CHARLES LEIGH PAULUS, citizens of the United States, residing, respectively, at Los Angeles and Dayton, in the counties of Los Angeles and Montgomery and States of California and Ohio, have invented certain new and useful Improvements in Lock Mechanism for Machine Guns, of which the following is a specification.

This invention relates to lock mechanism for machine guns, the object in view being to provide a means whereby the force necessary to trip the trigger of a machine gun is decreased to such an extent as to permit the trigger to be operated by the trigger motor of an electrical synchronizing gear.

With the above and other objects in view, the invention consists in the novel construction, combination and arrangement herein fully described, illustrated and claimed.

The accompanying drawing is a sectional view of the lock mechanism of a machine gun.

The invention consists in modifying the tumbler 1 and trigger 2 of a machine gun by forming the nose 3 of the trigger with a cam face 4 and also forming the notch 5 of the tumbler with a cam face 6 so that the trigger will be normally cammed out of the notch of the tumbler unless the movement of the trigger be resisted. This resistance is produced by a lever 7 which is mounted on a pivot 8 between the ends thereof and formed in one end with a substantially square notch 9 into which fits the correspondingly formed end of the trigger 2 as clearly shown in the drawing. The engagement between the trigger 2 and the lever 7 is such that there is no tendency to cam the trigger out of the notch 5 of the tumbler. Under the new arrangement, the force exerted by the top end of the trigger 2 against the lever depends upon the angle at which the nose of the trigger and the notch of the tumbler are bevelled and this force at the top end of the trigger may be made practically any value desired. The plunger of the electrical synchronizing gear trigger motor, (not shown) operates against a

projecting end portion 10 of the lever 7 and when such trigger motor plunger depresses such end of the lever it raises the opposite end of the lever clear of the end of the trigger and allows the tumbler 1 to cam the nose 3 of the trigger out of the notch of the tumbler which in turn permits the firing pin 11 to move forward priming the cartridge in the firing chamber. A spring 12 actuates the lever 7 and returns it to a position to again engage and hold back the trigger 2.

Having thus described our invention, we claim:

1. In lock mechanism for machine guns, the combination of a firing pin, a tumbler for said firing pin having a cam face, a trigger having a portion bearing against said cam face, and a trigger holding and releasing lever having a positive engagement with said trigger and having a projection for cooperation with the trigger motor of an electrical synchronizing gear.

2. In lock mechanism for machine guns, the combination of a firing pin, a tumbler for said firing pin having a cam face, a trigger having a cam faced portion bearing against said cam face, and a trigger holding and releasing lever having a positive engagement with said trigger and having a projection for cooperation with the trigger motor of an electrical synchronizing gear.

3. In lock mechanism for machine guns, the combination of a firing pin, a tumbler for said firing pin having a cam face, a trigger having a portion bearing against said cam face, and a trigger holding and releasing lever having a positive engagement with said trigger and having a projection for cooperation with the trigger motor of an electrical synchronizing gear, the contacting faces of the tumbler and trigger being such that the tumbler may cam the trigger out of holding engagement therewith when the trigger is released by said lever.

In testimony whereof we affix our signatures.

HERBERT O. RUSSELL.
CHARLES L. PAULUS.
